COMBINED PNEUMATIC RAFT AND SUN BATHING SUPPORT STRUCTURE

Willard S. Norton, 5680 NE. Oaktree Lane,
Kansas City North, Mo. 64104

Filed May 10, 1971, Ser. No. 142,121

Term of patent 14 years

Int. Cl. D12—99

U.S. Cl. D71—1 HH

FIG. 1 is a perspective view of a combined pneumatic raft and sun bathing support structure embodying my design.

FIG. 2 is a top plan view thereof.

FIG. 3 is a side elevational view thereof.

FIG. 4 is an end elevational view thereof.

FIG. 5 is a transverse sectional view thereof and taken on line 5—5, FIG. 2.

I claim:

The ornamental design for a combined pneumatic raft and sun bathing support structure, as shown.
